UNITED STATES PATENT OFFICE.

LOUISA P. WAGNER, OF NEW YORK, N. Y.

ELECTRIC SIGNAL-LAMP.

1,261,464.

Specification of Letters Patent. Patented Apr. 2, 1918.

Application filed November 17, 1916. Serial No. 131,977.

To all whom it may concern:

Be it known that I, LOUISA P. WAGNER, a citizen of the United States, and a resident of the city of New York, in the county of the Bronx and State of New York, have invented 5 certain new and useful Improvements in Electric Signal-Lamps, of which the following is a specification.

This invention relates to improvements in 10 signal lamps for automobiles and particularly to that class of such lamps which give a signal to the traffic in the rear of the car, of the direction in which the driver of the automobile intends to turn his car.

15 It is the object of this invention to provide a lamp or fixture for this purpose of utmost simplicity in design and operation; and with these and other objects in view the invention consists in certain novel details of 20 construction combination and arrangement of parts hereinafter described and set forth in the appended claims.

Reference is to be had to the accompanying drawing in which,

25 Figure 1 is a front elevation of my signal lamp.

Fig. 2, is a plan view of Fig. 1.

Fig. 3 is a side elevation of Fig. 1.

Fig. 4, is a detail showing the attachment 30 of the operating means for my signal lamp to the dashboard and steering apparatus of an automobile.

Fig. 5 is a detail showing the pilot lamps.

Fig. 6, is a plan of the push-buttons of the 35 snap-switches, operating pilot and signal lamps.

Fig. 7, is a side elevation of the housing of the snap switches.

Similar characters of reference indicate 40 the same parts throughout the various figures.

My signal lamp consists of an elongated casing 1 which may preferably be constructed of a plate of sheet metal, bent into such 45 shape that the rear part of said casing assumes a semicylindrical or parabolic shape at 1^a to form a reflector, for which purpose the inside may be suitably enameled or plated. The longitudinal edges of plate 1 are bent inwardly at a right angle to form 50 ledges 1^b adapted for the attachment of the front or lens-plate 2. The ends or vertical sides of the casing are formed by plates 1^c,

soldered or otherwise joined to plate 1 in any suitable manner. The interior of the 55 casing so formed is divided into a number of compartments by vertical, opaque division plates 3 of which two are shown on the drawing. The lens plate 2 consists of a rectangular plate, whose edges are bent, or 60 otherwise provided with flanges 2^a, extending away from the plate and forming a right angle with it, to fit over the edges of the casing. Plate 2 is provided with three openings, arranged concentric with each of the 65 compartments of the casing, and each of these openings is provided with a refractory lens, 3^a 3^b 3^c. Each of the compartments accommodates an electric signal lamp, 4^a, 4^b, 4^c, by means of a socket, which is supported 70 by an inlet nipple. The inlet nipples for lamps 4^a and 4^c pass through the end plates 1^c preferably through an aperture arranged central to the semicircle of their shape. The inlet nipple for lamp 4^b of the middle compartment, passes through an aperture in the curved part 1^a of plate 1 in axial alinement with the lens of the middle compartment. The walls of the casing are reinforced at the 75 inlet apertures for these nipples by reinforcing plates 5 and these are held by spherical supports, 6^a, 6^b, 6^c. The spherical supports 6^a and 6^c of the end compartments, are joined to the support 6^b, of the middle compartment by tubular members 7, bent to 80 form a curve at the corners of the casing. Support 6^b is provided with an extension-tube 8, arranged in alinement with the socket of lamp 4^b. This extension carries at its outer end, a flange 9 which serves to fasten 85 the signal lamp box to the rear board 10 of an automobile body, in suitable manner. The conductors which supply current to the signal lamps enter through flange 9 and extension 90 8 into support 6^b and from there through the tubes 7 to supports 6^a and 6^c to their respective lamps. Each of the signal lamps 4^a, 4^b, 4^c, is arranged in a series circuit with a small pilot lamp, 10^a, 10^b, 10^c, and a snap switch 11^a, 11^b, 11^c. These pilot 95 lamps are fastened to a small board 12 which is preferably arranged on the dash-board of the automobile, in front of the steering wheel, to be in plain view of the driver. The snap switches are preferably held in a 100 suitable housing 13 which is fastened to the 105

steering wheel support as shown in Fig. 4. The three lenses are preferably made of different colored glass, for instance 3^a on the left side green, 3^b in the middle red and 3^c white. The pilot lamp which is in the same circuit is colored the same as its signal lamp.

In operation my signal device operates as follows:

Should the operator of the automobile 10 wish to turn his car to the left, he would press button 11^a which lights the signal lamp 4^a in the left compartment and at the same time pilot lamp 10^a. Should he wish 15 to stop the car, he would press button 11^b lighting thereby lamp 4^b and pilot lamp 10^b and should he desire to turn to the right he would press button 11^c lighting lamp 4^c and pilot lamp 10^c. In every case a different 20 colored light will indicate to the traffic in the rear of his car the direction he intends to take, while the pilot lamp will indicate to the driver which of the lamps is lighted in the rear of his car.

While other devices to give similar signals, have been constructed, the advantages 25 of my device are to be found in the simplicity of its arrangement, and its attachment to the automobile; as there is only one attachment for the signal lamps to the car 30 to be made at flange 9. The curved tubular members which incase the conductors serve also as supports for the casing, giving a somewhat elastic but steady support for the same, particularly because each one of the 35 lamps and compartments is, independently of the others, connected to the supporting bracket, and the center nipple at 6^b holds the casing from turning about supports 6^a.

and 6^c and serves to strengthen the casing from bending and vibrating in its central 40 part.

Having thus described my invention, what I claim as new and desire to secure by Letters Patent is:

1. A signal lamp for automobiles comprising a casing, rectangular in longitudinal section and U-shaped in transverse section, transverse plates at the ends and within said casing, to form a plurality of compartments, an electric lamp supported in each compartment, a tubular bracket partly surrounding said casing, tubular connecting members extending through the end plates to the lamp in each end compartment, a tubular member extending through the curved side of an intermediate compartment to connect the lamp in said intermediate compartment with said bracket, a common support attached to said bracket to connect said casing to the body of an automobile and means to selectively 60 illuminate the lamp in each compartment.

2. In a signal lamp for automobiles, a U shaped casing consisting of a plate forming the top, rear and bottom of said casing, a plurality of transverse plates at the ends and within said casing to form a number of compartments, a cover plate adapted to fit over the front opening of said casing, apertures in said cover plate, concentrically arranged with each of said compartments, a refractory lens supported in each of said apertures, a tubular member forming a single support for said casing and inlet connections from said tubular member to each of said compartments.

LOUISA P. WAGNER.
